UNITED STATES PATENT OFFICE.

SYDNEY WROUGHTON FULTON, OF WEST TAIERI, NEAR DUNEDIN, NEW ZEALAND.

FENCE-WIRE STRAINER.

SPECIFICATION forming part of Letters Patent No. 310,505, dated January 6, 1885.

Application filed February 7, 1884. (No model.)

To all whom it may concern:

Be it known that I, SYDNEY WROUGHTON FULTON, of West Taieri, near Dunedin, New Zealand, have invented certain new and useful Improvements in Fence-Wire Strainers, of which the following is a full, clear, and exact description.

Reference is to be had to the accompanying drawings, forming part of this specification, in which similar letters of reference indicate corresponding parts in all the figures.

Figure 1 is a side elevation of my improved wire-strainer. Fig. 2 is a front elevation of the same. Fig. 3 is a rear elevation of the same. Fig. 4 represents a key for tying the strained wire.

The object of this invention is to provide a simple and convenient implement for tightening and straining the wires of wire fences.

The invention consists of a ring or frame carrying two pairs of clamping-jaws, and a wire-straining shaft or roll disposed on one side of the line of said jaws, and in details of construction, substantially as hereinafter more fully set forth and claimed.

A is an open ring nine inches (more or less) in diameter. The ring A is made of metal of such a width and thickness as will give it the necessary strength.

To opposite sides of the ends of the open ring A are riveted the ends of two connecting-bars, B, which are made with outward offsets to form a space or slot, C, to receive the short shaft D and the ratchet-wheel E; or the slot C may be otherwise formed. The shaft D is journaled to the bars B, and the ends of the said journals project and are squared to receive the wrench or lever F, by means of which the said shaft is turned. The ratchet-wheel E is formed upon or rigidly attached to the shaft D, or the journal of the said shaft.

To one of the bars B is pivoted a pawl, G, in such a position that it can be turned forward to engage with the teeth of the ratchet-wheel E and hold the shaft D from being turned back by the strain of the wire.

To the ring A is pivoted an eccentric, H, in such a position that it can be turned to clamp the wire against the end B' of the bar B. The eccentric H is provided with a lever-handle for convenience in turning it. To the

opposite part of the ring A is attached a stud, I, which is grooved to form a seat for the wire, and against which the said wire is clamped by the lever-eccentric J, pivoted to the said ring A.

K represents a key for use in tying the ends of the strained wire.

In using the implement the wire is secured to the fence-posts, and is then cut midway between the said posts, or at any other desired point. One part of the cut wire, near its end, is clamped between the end B' of the bar B and the lever-eccentric H, and the end of the other part of the said cut wire is passed through a hole, L, formed transversely in the shaft D, and the said shaft is turned by means of the lever F, to wind the said wire around the said shaft, and thus strain it. When the desired tautness has been given to the wire, the pawl G is turned against the teeth of the ratchet-wheel E, to hold the wire against slackening. The wire is then clamped between the stud I and the lever-eccentric J, the pawl G is turned back, and the wire is detached from the shaft D. The ends of the wire are then wound around each other, or otherwise tied by means of two keys, K, or other suitable means, and the strainer is detached from the wire. The surplus wire can be cut away before or after the tying, as may be desired.

I am aware that it is old to employ an oval form of frame with a wire-straining roll or shaft arranged transversely of and about centrally upon said frame, with the point of connection of the wire with said roll or shaft in the same line with the clamping or holding jaws, my invention differing from this form of strainer, in that the wire-straining roll or shaft acts upon the wire out of alignment with the clamping or holding jaws, whereby the action of said roll or shaft is rendered more effective and the straining operation is expedited.

Having thus described my invention, I claim as new and desire to secure by Letters Patent—

1. A fence-wire strainer constructed substantially as herein shown and described, and consisting of the ring or frame A, having slot C in its circumference, the shaft D, arranged in said slot, and having transverse perforation L, the lever F, and the clamps H B' and I J, said clamps being arranged individually

in line and out of line with the shaft D, as set forth.

2. In a fence-wire strainer, the combination, with the ring or frame A, having slot C in its circumference, of the shaft D, arranged in said slot, and having transverse perforation L, the lever F, the ratchet-wheel and pawl E G, and the clamps H B' and I J, arranged individual- 5 ly in line and out of line with the shaft D, sub-

stantially as herein shown and described, to whereby the wire can be put under any desired strain, as set forth.

SYDNEY WROUGHTON FULTON.
